UNITED STATES PATENT OFFICE

156,368

BOBBY PIN HOLDER

Lolita E. Primm, Chicago, Ill.

Application November 10, 1948, Serial No. 149,551

Term of patent 14 years

(Cl. D86—10)

To all whom it may concern:

Be it known that I, Lolita E. Primm, a citizen of the United States, residing at Chicago, in the county of Cook and State of Illinois, have invented a new, original, and ornamental Design for a Bobby Pin Holder, of which the following is a specification, reference being had to the accompanying drawing, forming a part thereof, in which:

Fig. 1 is a front elevational view of a bobby pin holder, showing my new design, and

Fig. 2 is a side elevational view thereof.

I claim:

The ornamental design for a bobby pin holder, as shown.

LOLITA E. PRIMM.
